UNITED STATES PATENT OFFICE.

WINFIELD B. PHILLIPS, OF FENTON, MICHIGAN.

DESIGN FOR A SCREEN-DOOR FRAME.

SPECIFICATION forming part of Design No. 30,544, dated April 11, 1899.

Application filed March 4, 1899. Serial No. 707,805. Term of patent 7 years.

To all whom it may concern:

Be it known that I, WINFIELD B. PHILLIPS, a citizen of the United States, residing at Fenton, county of Genesee, State of Michigan, have invented and produced a new and original Design for a Screen-Door Frame, of which the following is a specification, reference being had to the accompanying drawing, which forms a part of this specification.

10 The figure of the drawing is a plan view of a screen-door frame, showing my new design.

As shown in the drawing, the leading or material feature of my design consists of and comprises the entire screen-door frame, and 15 embodies a rectangular frame A, the lateral sides of which are connected intermediate the extremities thereof by upper and lower transverse bars B B'. Between said bars are located a series of beaded ball-spindles, which 20 consist of a spindle C and a ball C' interme-

diate the extremities of the spindle. In the corners of the frame A are ornamental brackets D, each having a beaded drop (indicated at d) inserted therein. In the corners formed by the sides of the frame A and by the transverse bars B B' are similar brackets D, each provided also with a beaded drop d. The brackets are shown of scrollwork in outline.

Having described my invention, what I claim as new, and desire to secure by Letters 25 Patent, is—

The design for a screen-door frame, as herein shown and described.

In testimony whereof I sign this specification in the presence of two witnesses.

WINFIELD B. PHILLIPS.

Witnesses:

II. J. PHILLIPS,
II. B. LATOURETTE.
